UNITED STATES PATENT OFFICE.

ASA M. FITCH, OF SEYMOUR, INDIANA.

DESIGN FOR A BOX.

SPECIFICATION forming part of Design No. 17,146, dated March 1, 1887.

Application filed October 9, 1886. Serial No. 215,814. Term of patent 7 years.

To all whom it may concern:

Be it known that I, ASA M. FITCH, a citizen of the United States, and a resident of Seymour, in the county of Jackson and State of Indiana, have invented a certain new and original Design for Boxes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my box as closed, and Fig. 2 is a plan view of the same when open.

My design relates to boxes, as fully shown in the accompanying drawings, in which the same letters of reference indicate corresponding parts in both figures, as will be hereinafter more fully set forth.

A represents the bottom of the box, which is of an oblong shape, having parallel sides and ends and having its corners cut off, as shown at B. The rim of the box, C, corresponds exteriorly with the outline of the bottom A; but its interior is of a rectangular shape, and may inclose a series of rectangular-shaped fields, each having an ornamental border, E. Upon the upper edge of each end of the rim 30 C, which is wider than the sides, is a field, D, the sides of which are parallel with the outer and inner sides of the ends, and the ends of the fields are parallel with the cut-off corners B. Each of these fields is adapted to receive 35 words or letters.

The lid or cover of the box consists of two flat rectangular pieces, F F, one corner of each end of which is cut off at an angle to correspond with the cut-off corners of the bottom and rim. The top or outer side of each of these covers is divided into three fields, each adapted to receive an ornament, as photographs or representations of flowers, &c., and each having an ornamental border corresponding with the outline of the field and parallel therewith. The central or largest of these fields is of a rectangular shape, and the end fields are all similar to each other and in the form of a trapezoid. The interior or under 45 side of each of said covers has a field corre-

sponding with the shape and outline of the cover, each of said fields being provided with scrolls, all of which are adapted to receive words or characters.

Having thus described my design, I claim—

1. The herein shown and described design for a box, consisting of a bottom oblong in shape and having its corners cut off, a rim having its exterior corresponding with the outline of the bottom and having its interior 60 in the shape of a rectangle, the upper end of each edge of said rim being wider than the sides and provided with a field adapted to receive words or letters, and two rectangular covers, each having a corner cut off at each 65 end.

2. The herein shown and described design for a box, consisting of a bottom oblong in shape and having its corners cut off, a rim having its exterior corresponding with the 70 outline of the bottom and having its interior in the shape of a rectangle, the upper edge of each end of said rim being wider than the sides and provided with a field adapted to receive words or letters, and said rectangular 75 interior inclosing rectangular fields, each having an ornamental border, and two rectangular covers, each having a corner cut off at each end.

3. The herein shown and described design 80 for a box, consisting of a bottom and a rim, the exterior of which is in the shape of an irregular polygon, and two rectangular covers, each having a corner at each end cut off, the top or upper side of each of said covers being divided into three fields, each having an 85 ornamental border and adapted to receive ornaments.

4. The herein shown and described design for a box, consisting of a bottom and a rim, 90 the exterior of which is in the shape of an irregular polygon, and two rectangular covers, each having a corner at each end cut off, the top or upper side of each of said covers being divided into three fields, the middle field 95 being rectangular in shape and adapted to receive a photograph, and each of the end fields having its outline in the form of a trapezoid, and each adapted to receive representations of flowers.

5. The herein shown and described design for a box, consisting of a bottom and a rim, the exterior of which is in the shape of an irregular polygon, and two rectangular covers, each having a corner at each end cut off, the inner side of each of said covers having a field in which are scrolls, each adapted to receive letters or characters.

In testimony that I claim the foregoing as my own I have hereunto affixed my signature to in presence of two witnesses.

ASA M. FITCH.
